UNITED STATES PATENT OFFICE.

SEVERIANO ANTONIO DE CASTILHO, OF RIO DE JANEIRO, BRAZIL.

ORDNANCE BREECH MECHANISM.

1,090,449.

Specification of Letters Patent. Patented Mar. 17, 1914.

Application filed April 9, 1913. Serial No. 759,895.

To all whom it may concern:

Be it known that I, SEVERIANO ANTONIO DE CASTILHO, a citizen of the Republic of Brazil, residing at R. Viama 40, S. Christoval, Rio de Janeiro, Brazil, but at present temporarily residing at Villa Laura, Kingsland, Clayton Road, Jesmond, in the city and county of Newcastle-upon-Tyne, England, naval engineer, have invented certain new and useful Improvements in or Relating to Ordnance Breech Mechanism, of which the following is a specification.

This invention relates to ordnance breech-mechanism.

One type of breech-block at present used in ordnance breech-mechanism is fashioned with, or is stepped axially or lengthwise to form, two portions of different diameters or sizes and both parallel or both tapered or coned or one parallel and the other tapered or coned, said portions being provided with interrupted or segmental screw-threads so arranged that the interruption, spaces or plain parts on one portion do not align with those on the other portion. In another type of breech-block which is not so fashioned or stepped axially or lengthwise the interrupted or segmental screw-threads are stepped radially, such radially-stepped interrupted or segmental screw-threads being known as "Welin" threads.

The object of this invention is to provide a breech-block which will combine the advantage of the two types referred to and according to the invention, I fashion the breech-block with, or step it axially or lengthwise to form, two or more portions of different diameters or sizes, and I provide said portions with "Welin" or radially-stepped interrupted or segmental screw-threads so arranged that the interruptions, spaces or plain parts on one portion do not align with those on the other portion or portions.

I will fully describe my invention with reference to the accompanying drawings wherein—

Figure 1 is a side view of one form of breech-block in accordance therewith, and Fig. 2 is an end view of Fig. 1.

Referring to the drawings the breech-block illustrated is fashioned with two portions *a* and *b* of different diameters, the rear portion *a* having the greater diameter. The peripheries of the two portions *a* and *b* are each provided with the well-known "Welin"

or radially-stepped interrupted or segmental screw-threads *a'*, *a²* and *b'*, *b²* respectively, which threads however are so arranged that the interruptions, spaces or plain parts *a³* on the portion *a* do not align or coincide with the interruptions, spaces or plain parts *b³* on the other portion *b*. The diameters of the two portions *a* and *b* are such that the diameter across the outermost screw-threads *b'* of the portion *b* does not exceed the diameter across the interruptions, spaces or plain parts *a³*. The threads *a'*, *a²* and *b'*, *b²* are preferably so arranged that the threads *b'* align with the interruptions, spaces or plain portions *a³*, the threads *b²* align with the threads *a'*, and the interruptions, spaces or plain parts *b³* align with the threads *a²*. A gap is shown disposed in front of a threaded part of the smallest radius on the larger axial step. The gaps are so disposed that the threaded portion extends from end to end of the plug axially in certain places.

If desired the block may be fashioned with more than two portions of different diameters having the screw-threads thereon arranged as above described, and each portion may be provided with more than two segments of radially-stepped interrupted or segmental screw-threads. Further, both or all the portions of the block may be parallel as illustrated, or both or all may be tapered or coned, or one or more may be parallel and the other or others may be tapered or coned. The breech of the gun to which the block is fitted is of course correspondingly fashioned, and it will be seen that when the block is closed and locked within the breech of the gun, it will be in engagement with and supported by the breech at some part or other along every portion of its periphery.

What I desire to claim by Letters Patent is:

1. A breech block fashioned with a plurality of portions of different diameters, said portions being provided with radially stepped interrupted threads that is having plain parts and threaded parts so arranged that the plain parts on one portion are out of alignment with the plain parts of another portion, the construction being such that the threaded portion extends from end to end of the plug axially in certain places.

2. A breech block fashioned with a plurality of portions of different diameters said portions being provided with radially

stepped interrupted threads, that is having plain parts and threaded parts, so arranged that the plain parts of one portion are out of alinement with the plain parts of another portion, one of said portions being tapered, the construction being such that the threaded portion extends from end to end of the plug axially in certain places.

3. A breech block fashioned with a plurality of portions of different diameters said portions being provided with radially stepped interrupted threads, that is having plain parts and threaded parts, so arranged

that the plain parts of one portion are out of alinement with the plain parts of another portion one of said portions being parallel, the construction being such that the threaded portion extends from end to end of the plug axially in certain places.

In witness whereof, I have hereunto signed my name in the presence of two subscribing witnesses.

SEVERIANO ANTONIO DE CASTILHO.
Witnesses:

FRED H. DUKE,
H. NIXON.
